UNITED STATES PATENT OFFICE.

CECIL EDGAR CAWLEY, OF PARSONS, KANSAS.

AIR CONTROL FOR CARBURETORS.

Application filed March 6, 1923. Serial No. 623,206.

To all whom it may concern:

Be it known that I, CECIL EDGAR CAWLEY, a citizen of the United States of America, residing at Parsons, in the county of Labette 5 and State of Kansas, have invented certain new and useful Improvements in Air Controls for Carburetors, of which the following is a specification.

This invention relates to new and useful 10 improvements in air controls for carburetors and has reference to an automatically operating device positioned in the air intake pipe for the carburetor at a point intermediate the carburetor and the stove associated with 15 the exhaust manifold.

The primary object of the invention resides in the provision of an air control for carburetors wherein a tensioned valve plate 20 when in its closed position is so constructed as to permit a limited quantity of air to flow thereby, and to be automatically opened to permit the passage of a greater quantity of air by suction created in the carburetor.

With the above and other objects in view 25 as the nature of the invention is better understood, the same consists of the novel form, combination and arrangement of parts hereinatfer more fully described, shown in the accompanying drawing and claimed.

30 In the drawing, wherein like reference characters designate corresponding parts throughout the several views,

Figure 1 is a side elevational view of an 35 air control for carburetors, a portion of the air pipe associated with the carburetor being shown in section, and the carburetor and associated engine structure being illustrated by dotted lines,

Figure 2 is a side elevational view of the 40 air control attached to a pipe section depending from the stove for the air supplied to the carburetor,

Figure 3 is a sectional view taken on line 45 III—III of Fig. 2 showing the spring for retaining the plate valve of the air control in its closed position, the plate valve being illustrated by dotted lines in an open position,

Figure 4 is a bottom plan view of the air 50 control, showing the oval formation of the plate valve providing constant laterally positioned air passages through the control, and

Figure 5 is a sectional view taken on line 55 V—V of Fig. 4.

It is the primary object of the present in-

vention to provide an air control for carburetors associated with automobile engines for the purpose of reducing the consumption of gas, suction created in the carburetor due 60 to increased speed of the gas engine providing for an increased supply of air to the carburetor for proper mixture with the gasoline drawn therein, the air control being entirely automatic in its operation and 65 positioned within the air supply pipe for the carburetor at a point intermediate the carburetor and the stove associated with the exhaust manifold.

Referring more in detail to the accompanying drawing, there is illustrated by dotted lines, a carburetor 1 having an air supply pipe 2 connected thereto as shown in Fig. 1, a stove 3 arranged adjacent the exhaust manifold of the gas engine being arranged 70 adjacent the upper open end of the air supply pipe 2, the stove carrying a depending relatively short pipe section 4 while the air control device is associated with the upper end of the air supply pipe 2 and the pipe 75 section 4 as shown in Fig. 1.

The air control embodies a cylindrical collar 5 having an enlarged coaxial flange 6 upon its upper end to receive the lower end 80 of the stove pipe section 4, the collar 5 being positioned in the open upper end of the air pipe 2 and retained therein.

An automatically opening plate valve is 85 associated with the lower open end of the collar 5, the plate valve opening outwardly 90 of the collar and into the air pipe 2 by suction created in the carburetor 1, the plate valve 7 being hingedly connected at 8 to one side edge of the lower end of the collar 5, and being of oval formation as shown in 95 Fig. 4 to provide constantly open air passage 9 through the carburetor. To retain the plate valve 7 in its normally closed position as shown by full lines in Fig. 3, a coil spring 10 is anchored at one of its ends at 11 to a side wall of the collar adjacent the flanged end 6 thereof and in line with the hinge connection 8, the other end of the spring 10 being attached at 12 to the free 100 swinging end of the plate valve 7.

With a device of this character positioned in the intake pipe that supplies air to a carburetor, and by forming the plate valve 7 of oval formation in plan view as shown in Fig. 4, a constant supply of air is delivered 110 to the carburetor when the engine is running at a low speed, and when a larger quantity

of gas is delivered to the engine, the suction created in the carburetor automatically opens the plate valve 7 against the tension of the spring 10 for drawing in an increased supply of air, permitting the engine to operate with a leaner mixture of gas, reducing the gasoline consumption and automatically providing the proper mixture.

While there is herein shown and described the preferred embodiment of the present invention, it is nevertheless to be understood that minor changes may be made therein without departing from the spirit and scope of the invention as claimed.

15 10 What is claimed as new is:—

In an air control for carburetors, the combination with the outer end of an air feed pipe for a carburetor and a hot air stove having a pipe extension, of means for controlling the flow of air through the hot air pipe interposed between the outer end of the hot air pipe and pipe extension carried

by the stove and telescopically associated with each member, said air controlling means including a collar, an annular enlargement 25 at one end thereof inclosing the pipe extension on the hot air stove with the collar extending into the outer end of the hot air pipe, an outwardly opening plate valve hinged at one end at the inner end of the 30 collar with the free swinging edge thereof overlying the inner edge of the collar to form an abutment for the plate valve during closing movement, the collar being circular and said valve being oval to provide 35 constant air passages at opposite sides of the valve plate and a coil spring anchored at one end to the outer end of the collar and having its other end secured to the plate valve adjacent the swinging edge for normally holding the valve in closed position 40 engaging the inner end of the collar.

In testimony whereof I affix my signature.
CECIL EDGAR CAWLEY.
